UNITED STATES PATENT OFFICE

CHARLES A. FISHER AND CLETUS J. KETNER, OF KANNAPOLIS, NORTH CAROLINA, ASSIGNORS TO CANNON MILLS COMPANY, OF KANNAPOLIS, NORTH CAROLINA, A CORPORATION OF NORTH CAROLINA

JACQUARD HEAD

Application filed June 16, 1930. Serial No. 461,552.

This invention relates to a new and improved jacquard head having as its main object to decrease the number and amount of pattern cards usually necessary in making a pattern. The improved jacquard head is designed to be positioned directly above the loom upon suitable arches supported by the loom frame and is positioned in such proximity to the loom that the operator will have no difficulty in reaching any part thereof while standing on floor.

The machine shown is of the double lift single cylinder type, entirely automatic in operation, and is capable of being operated at a much higher speed than previous machines doing the same type of work.

An important object of the invention is to provide a novel arrangement to move the standard jacquard cards one row at a time and also to provide means whereby the distance between two connected cards may be traversed without slowing up the operation of the machine or interfering with the operation.

It is a prime object to construct a jacquard head of exceedingly compact formation, being substantially less in height and depth than the usual jacquard heads now used. The reduction in the height of the machine is mainly accomplished through a new design for the hooks themselves together with modifications in the grate, and the reduction in width of the jacquard head is due mainly to a novel and improved card cylinder which is designed to furnish substantially a line contact with the surface of the cards and which is also designed so as to have its circumference and diameter proportional to the width of each card. A guide cylinder for the cards is positioned in such a location so as to cooperate with the exceedingly small size card cylinder to prevent any bending of the cards.

The needles in the improved jacquard head are also designed so as to support two hooks without aid from the other needles and hooks, as is done in the regular jacquard head.

It is an important object of the invention also to provide means whereby, due to the increased speed of the cylinder the feed of

the cards will be satisfactory at all times and the cards cannot jump off the cylinder pegs.

It is also designed to provide a special type of hook having a cut-out portion at the bottom thereof so as to allow sufficient room for the movement of the bottom of the hook while the top of the hook is held by a raised griff bar. This construction eliminates the necessity for providing resiliency in the hooks themselves and also permits a much shorter hook to be used in the machine.

With these and other objects in view as will become apparent from the detailed description following, the invention consists in the combination and arrangement of parts set forth below, claimed in the claims and shown in the drawings, in which

Figure 1 is a side elevational view of the improved jacquard head,

Figure 2 is a partial cross-sectional view with certain parts shown in elevation, showing particularly the means employed for securing exact registry of the card holes,

Figure 3 is a vertical cross-sectional view through the jacquard head looking towards the cylinder advancing mechanism,

Figure 4 is a plan view,

Figure 5 is a side elevational view taken from the opposite side to that shown in Figure 1,

Figure 6 is a plan view of the grate used,

Figure 7 is a cross-sectional view taken upon the line 7-7 in Figure 6,

Figure 8 is an elevational view of a hook used in the head, and

Figure 9 is a plan view of a needle.

In the drawings, in which similar reference characters are used to denote like parts, 10 indicates the frame generally, by which the various mechanisms are supported. The frame consists of two side elements 11 and 12 which are joined together by brace rods 13. The legs of the side frames 11 and 12 are preferably provided with right angular lugs 14 which are adapted to be secured to suitable arches 15 supported by the loom frame by the bolts 16.

Two griff knives 17 and 18 are provided which are secured at each end by a bolt and nut connection 19 to the slide rods 20 sliding

80

90

95

100

in bearings 21 and 22 provided in the side frames 11 and 12.

The slide rods 20 are alternately raised and lowered carrying with them the corresponding griff knife by means of a connection between the bell-crank lever 23 and the cam shaft of the loom, not shown. The bell-crank 23 is fixedly connected at its elbow to a shaft 24 which in turn rotates in bearings provided in the bearing blocks 25 secured to the side frames 12 and 11. The bearing blocks 25 are preferably secured to the side frames by one of the brace rods 13 passing through the side frames. A lever 26 is pivotally connected to the upper end of the bell-crank 23 and the other end is pivotally connected to another lever 27 which is adjustably fixed by a set screw or otherwise to a shaft 28 extending between the side frames 11 and 12 at the upper part thereof. Any oscillation of the bell-crank 23 will be transmitted to the shaft 28. At each end of the shaft 28 upon the outside of the side frames 11 and 12 a walking beam 29 is fixedly secured by a set screw 30 or otherwise and each end of the walking beam 29 has pivotally secured thereto a lever 31. The other end of each of the levers 31 is secured pivotally to a block 32 adjustably fixed upon the rods 20. The construction outlined permits the alternate raising and lowering of the griff bars 17 and 18.

The side frames 11 and 12 are provided with outwardly directed apertured lugs 33 which serve as bearings for the slide rods 34 which move the card cylinder 35 towards and away from the needles 36 projecting through the needle board 37. One end of the slide rods 34 is preferably threaded, not shown, and has secured thereto the cylinder stand indicated generally at 38. An independent cylinder motion mechanism is employed operated from the crank shaft of the loom and will now be described. A block 39 is fixed adjustably to each of the slide rods 34 between the bearings 33 and a lever 40 is pivotally secured to each of the blocks 39 while the other end of the lever 40 is pivotally secured to the upper end of a lever 41 which in turn is adjustably, fixedly secured by a set screw 42, or by any other suitable means to a shaft 43 which is also provided with bearings in the bearing blocks 25, previously described. The shaft 43 has fixedly secured thereto a lever 45 which can be connected by any desired means to the crank shaft of the loom. An oscillating movement of the lever 45 will cause a reciprocating movement of the rods 34 carrying the card cylinder. The oscillating movement of the lever 45, due to the motion of the crank shaft of the loom, will cause a uniform movement of each end of the card cylinder due to the fact that the shaft 43 has connected at each end thereof

similar levers 41, 40 and the blocks 39 secured to the slide rods 34.

The card cylinder 35 is integral and preferably made from metal having a series of circular grooves therein into which the ends of the needles 36 may project when permitted to do so by a perforation in the jacquard card. Bearing blocks 46 are fixedly secured in the cylinder stands 38 and the ends of the cylinder are located therein. At each end of the cylinder adjacent the groove portion the pegs 47 are provided for cooperating with the peg holes upon the cards for advancing the card one row of holes upon each pick.

Secured to one end of the cylinder fixedly between the bearing for the cylinder and the pegs is a ratchet wheel 48 of a peculiar construction. The ratchet wheel has eleven teeth 49 in the present instance which are similar in construction, while the twelfth tooth 50 is of considerably larger size. The standard jacquard card is provided with twelve rows of apertures and each card is laced to its neighboring card through the lace holes provided at both ends and at the center. The eleven teeth of the same size upon the ratchet wheel 48 will progressively advance the standard jacquard card from row to row in said card, while the twelfth tooth will advance the cards from the one which has been entirely exhausted to the next succeeding card. An actuating pawl 51 is pivoted to a rod 52 which is secured to the side frame 12 by the nut 53.

The movement of the cylinder towards and away from the needle board 37 will cause the gravity actuated pawl 51 to advance the cylinder one step upon each reciprocation of the cylinder. The advancing of the card through means of the pegs upon the cylinder takes place upon the movement of the cylinder away from the needle board 37.

It is, of course, obvious that means must be provided for maintaining the card in fixed position during the movement of the card towards the needle board and needles. This means is provided at the other end of the cylinder from that upon which the ratchet wheel above described is located and consists of a disk 54 upon the surface of which are provided a series of semi-circular recesses 55 as shown more particularly in Figure 2. Twelve recesses are provided and two of these recesses are spaced a greater distance apart than the space between the others in order to take care of the transfer from the completed card to a new card. The larger space 56 between two recesses 55 corresponds with the larger tooth 50 provided in the ratchet wheel above described. The disk 54 is fixedly adjustably secured to the cylinder. A roller element 57 is designed to cooperate with the recesses 55 so as to hold the cylinder

non-rotatable during its motion towards the needles, and the roller element 57 is carried by a lever 58 pivoted upon shaft 59.

The downwardly extending arm 60 secured to the cylinder stand 38 has secured thereto an arm 61 extending at right angles to the arm 60, to one end of which is secured a tension spring 62. The other end of the tension spring 62 is secured to the arm 58 so as to constantly urge the arm 58 with the roller 57 towards the disk 54. A similar arm 60 extends downwardly from the cylinder stand 38 located adjacent the ratchet mechanism and the lower ends of the arms 60 are connected by the above mentioned shaft 59. The shaft 59 has adjustably secured thereto at points in alignment with the pegs upon the cylinder two leaf springs 63. The leaf springs 63 are provided with slots 64 through 20 which the points of the pegs extending beyond the thickness of the card may project. Upon reference to Figure 3 it can be seen that the cylinder is of such small size that it provides merely a line contact against the 25 cards at the point at which the needles come in contact with the card. In order to secure a proper feeding of the cards it is obvious that the cards must be fed towards the cylinder in a novel manner. For this purpose a 30 guide cylinder 65 is provided located approximately fourteen inches above the cylinder in the position shown. The guide cylinder is mounted upon any desired construction so as to be freely rotatable. The motion 35 of the guide cylinder 65 is therefore dependent upon the pull upon the cards by the pegs upon the cylinder.

The guide cylinder may be of any desired form, but is preferably constructed so as to 40 have five faces, each of these faces being exactly the width of the standard jacquard card. It is therefore apparent that, due to the cooperation of the guide cylinder with the peculiar type of card cylinder employed, 45 the cards can be fed to the cylinder without any bending of the cards taking place. The cards are shown at 66 and the lacing between the cards is illustrated diagrammatically at 67. The springs 63 will maintain the cards in close contact with the card 50 cylinder and the leaf springs 63 are of such length and shape as not to bend the card out of shape. The hooks 69 are of the shape shown more particularly in Figure 8 and 55 comprise an upper curved end 70 and a lower end 71 of substantially wide construction provided with the hook end 72 adapted to rest upon the grate. The wide end 71 is cut away as at 73 and tapers down to the 60 narrow portion 74 in which is an aperture 75 in which is secured the neck cord for the harness. The wire portion 76 of the hook can be secured to the wide portion 69 by welding or any other desired means. The 65 entire length of the hook is substantially less

than the length of the standard hooks used in jacquard heads at the present time. In fact, the reduction in length amounts to substantially twelve inches. Due to this considerable decrease in the length of the hooks it is 70 possible to greatly decrease the entire height of the jacquard head.

Each of the legs of the side frames 11 and 12 is provided with inwardly projecting lugs 77 which form the supporting surface for 75 the grate 78. The grate is of a peculiar structure, as shown more particularly in Figures 6 and 7, and comprises the supporting arms 79 at each corner thereof in which are provided apertures 80. Bolts 81 with 80 cooperating nuts are passed through the slots 80 and corresponding apertures provided in the lugs 77 in order to secure the grate in position. The grate 78 is provided with a medial rib 82 and with another rib 83 located in advance of the rib 82 upon which the hook portions 72 of the hooks are designed to rest when in their lowermost position. A shoulder portion 84 is provided in back of the medial rib 82 and a series of slots 85 85 are formed in the grate between the ribs 82 and 83 and between the rib 82 and shoulder 84. These slots are considerably longer than the usual slots provided because, due to the lack of resiliency in the hook construction itself, it is necessary to provide a considerably larger working space whereby the hook can be shifted at the bottom when the hook is supported in upper position by one of the 90 griff knives. The cut away portions 73 in the hooks themselves also aids in allowing of a further tilting movement of the hooks when in raised position, and when urged backwardly at the bottom by a needle, which in turn is forced back by the card upon the 95 cylinder. There is therefore a distinct cooperation between the small size of the hooks and the larger slots provided in the grate.

In Figure 9 a plan view of a needle 36 is shown having a projecting end 86 at the 100 front thereof which projects through the needle board 37 and at the rear end a cut away portion 87 of slightly larger cross section is provided in order to accommodate the coil spring 88 which constantly urges 105 the needle forwardly. The coil spring 88 abuts against the shoulder 89 provided upon the needle itself and against the spring board 90 extending between the two side frames 11 and 12 and secured thereto in any 110 desired way, preferably by bolts. Apertures are of course provided in the spring board 90 through which the ends 87 of the needles may project when forced backwardly by the card upon the cylinder. Each needle 115 is provided with two apertures 91 in which the wire portions 76 of two hooks are located. Each needle supports two hooks without any aid from other needles and hooks. This is distinct from the regular 120 125 130

jacquard head construction in which the needles support the adjacent hooks.

By the construction above outlined, as the cylinder presents a pattern card while one griff knife is at its lower position and the other griff knife is at its upper position to the needles, the hooks resting upon the grate are pivoted at their upper end away from the lower griff knife while the hooks supported by the upper griff knife are pivoted at their lower ends, due to the cut-out 73 and the larger size slot in the grate, without the necessity of bending or placing the hooks under tension.

It is obvious that various changes and modifications may be made in the invention above set forth, but it is understood that all such changes and modifications are claimed as will come within the spirit and scope of the following claims.

I claim:

1. In a jacquard head for looms, a reciprocating cylindrical line contact card cylinder having a diameter substantially less than the width of a standard card, means for rotating said cylinder the distance between adjacent horizontal holes upon a card upon each pick of the loom and means for advancing said cylinder after a card has been exhausted from the last horizontal row of holes in the exhausted card to the first horizontal row of holes in a new card.
2. In a jacquard head for looms, a frame, a reciprocating cylindrical line contact card cylinder having a diameter substantially less than the width of a standard card, a ratchet wheel fixed to said cylinder, a pawl pivoted to said frame for advancing said cylinder the distance between adjacent horizontal rows of apertures upon said card and said ratchet wheel having an enlarged tooth so that when said tooth is engaged by said pawl said cylinder will be advanced from one card to an adjacent card with the apertures therein placed in proper alignment with the needles.
3. In a jacquard head, a hook having an enlarged grate portion and said grate portion being cut away so as to allow greater pivoting of said hook when suspended from a griff knife in upper position when actuated by a needle.
4. In a jacquard head a hook having a wire portion and a grate portion, said grate portion having a substantial width and being cut away so as to taper to the neck cord securing end to permit of greater pivoting of said hook when actuated by a needle.
5. In a jacquard head for looms, a grate having enlarged hook slots and hooks having cut away portions located in said slots whereby the height of said head may be considerably reduced.
6. In a jacquard head for looms, a grate having enlarged hook slots, hooks having cut away portions located in said slots,

needles controlling said hooks, a cylinder for actuating said needles of a diameter substantially less than the width of a standard card and a guide cylinder for the cards located in such position as to render said cards less likely to be bent when moved by said cylinder.

7. In a jacquard head for looms, a cylinder of substantially small diameter so as to make a line contact with the cards, pegs upon said cylinder cooperating with the peg holes upon said cards, resilient means encircling said pegs maintaining said cards in close contact with said cylinder surface and means cooperating with said cylinder to render said cards less liable to be bent when carried past said needles.

In testimony whereof we have signed our names to this specification.

CHARLES A. FISHER.
CLETUS J. KETNER.
